PROCESS FOR THE RECOVERY OF PLUTONIUM

Herbert A. Potratz, St. Louis, Mo., assignor to the United States of America as represented by the United States Atomic Energy Commission

No Drawing. Application October 23, 1946
Serial No. 705,254

12 Claims. (Cl. 260—429.1)

This invention relates to a method for the recovery of plutonium from solutions containing the same. More particularly it is concerned with a method for separating plutonium in a substantially uranium free state from solutions containing uranium, fission products, and other impurities commonly associated therewith wherein the uranium is converted to a non-carriable or non-interfering state.

This is a continuation in part of co-pending application U. S. Serial No. 565,991, filed November 30, 1944, and any subject matter appearing therein common to the subject matter disclosed herein is incorporated by reference.

It is known that when uranium is subjected to neutron bombardment there is formed in small quantities a new element having an atomic weight of 239 and atomic number of 93, known as neptunium (symbol Np). This new element by radioactive decay is transformed through a half-life of 2.3 days to a further new element known as plutonium (symbol Pu) having an atomic number of 94. The particular isotope of this second new element has a mass of 239. In addition, certain other elements are formed as a result of fission of the uranium 235 nucleus such elements being referred to as fission fragments or, including radioactive decay products thereof, as fission products. The fission fragments or products are radioactive isotopes which may be included in two general element groups, a "light" fission fragment comprising elements having atomic numbers from about 35 to 46 such as bromine, krypton, rubidium, strontium, yttrium, zirconium, columbium, molybdenum, masurium, ruthenium, rhodium and a heavy fragment comprising elements having atomic numbers from about 51 to 60 such as antimony, tellurium, iodine, xenon, caesium, barium, lanthanum, cerium, praseodymium and neodymium. The fission fragments are usually present in radioactive form, ordinarily having a very short half-life, and by radioactive decay many of the fission fragments form other short lived products. As a result the radioactivity of the mass of uranium remains at a high and very dangerous level for some time following the neutron bombardment. It is particularly desirable to separate the plutonium from the radioactive fission products thereby removing from the mass the radioactive materials and particularly the light elements such as light metals having very short half-lives and consequently high radio-activities. Thus the product obtained by neutron bombardment comprises a major portion of uranium together with minor portions rarely in excess of one or two percent by weight of fission products and element 94 together with a smaller concentration of element 93. The recovery of element 94 in a concentrated form involves the separation of that element from such a product without excessive loss of element 94.

The removal of fission products from plutonium is of particular interest since they retain their radioactivity for a substantial time after the neutron bombardment. Such radioactivity is so intense that it is exceedingly hazardous to personnel engaged in working therewith.

A further problem which is frequently encountered involves the removal of impurities which may be present in plutonium concentrates. Such impurities may comprise residual uranium and/or fission products and/or agents used to assist in the separation of the plutonium from the irradiated uranium and may include numerous light elements including lithium, magnesium, sodium, calcium, silicon, beryllium, etc.

It is an object of the present invention to effect a relatively clean separation of the plutonium from the uranium and fission products wherein said plutonium is removed from solutions containing uranium and fission products as impurities.

It is a further object of the present invention to provide a simple method for removing plutonium from aqueous solutions particularly from other interfering substances.

In the process described and claimed in the co-pending application referred to above plutonium is readily removed from solutions containing fission products and uranium by adding an aqueous solution of cupferron thereto, thereby forming a precipitate substantially of plutonium cupferride together with uranium as a contaminant. This plutonium is next extracted from the precipitate by contacting the entire mixture of precipitate and mother liquor with several separate solutions of substantially water immiscible solvents for the plutonium cupferride. While this procedure functions very effectively to remove the plutonium from such solutions it does not result in the procurement of a product that is substantially free from uranium inasmuch as appreciable concentrations of the latter tend to follow the plutonium through each stage of the recovery process.

It has now been discovered that plutonium can be recovered in a substantially uranium-free condition from solutions containing uranium and other common impurities by adding ammonium carbonate to the initial plutonium-containing solution preferably in a slight excess over the amount required to neutralize said solution prior to the removal of the plutonium with cupferron. Under the above conditions the uranium is rendered non-carriable by cupferron thereby resulting in the obtainment of substantially pure precipitate of plutonium cupferride.

In carrying out a preferred embodiment of the present invention a 20% uranyl nitrate hexahydrate solution, prepared if desired by dissolving neutron irradiated uranium in nitric acid, is first subjected to the action of a suitable reducing agent such as, for example, hydrogen peroxide, hydroxylamine hydrochloride, or the like, in order to reduce any hexavalent plutonium which might be present to the +4 state. Thereafter a saturated solution of ammonium carbonate is added until the resulting solution gives a permanent alkaline reaction. Ordinarily an excess of ammonium carbonate in a concentration of approximately 5 to 10% over the amount required to neutralize the solution will be found sufficient and it is to be understood that the phrase "slight excess" as applied to the ammonium carbonate concentration mentioned herein is contemplated to imply concentrations not substantially in excess of 10% of the final mixture. In the majority of instances, however, highly satisfactory results may be obtained by introducing sufficient ammonium carbonate to bring the pH of the solution to a value of about 8.

On initially adding the ammonium carbonate to the acid solution a precipitate of uranyl double carbonate is generally observed to form. However, by introducing additional ammonium carbonate said precipitate goes back into solution and under such conditions the uranium exists in a highly soluble non-carriable state, probably in the form of a complex.

In instances where there is some question as to whether or not all of the uranium is in the hexavalent state prior

to the addition of ammonium carbonate an oxidizing agent which will not affect the valence of plutonium should be employed. Nitric acid is an example of a suitable oxidizing agent for this purpose. Also, when working with solutions in which at least a portion of the plutonium contained therein is in the -6 state, said solutions should be permitted to stand at least one-half hour after a suitable reducing agent has been added thereto. As examples of reducing agents suitable for this purpose there may be mentioned ferrous ion, hydroxylamine hydrochloride, iodide ion, and the like.

After the plutonium is removed from solution by the addition of cupferron, usually in the form of a dilute aqueous solution, to form a precipitate of plutonium cupferride after which a precipitate may be extracted from the resulting mixture by agitation with a substantially water immiscible organic compound, i. e., a selective solvent for plutonium cupferride. Alternatively, the plutonium may be removed from such solutions by adding the cupferron thereto in the form of a dilute solution in the water immiscible liquid organic solvent for plutonium cupferride whereby the plutonium cupferride passes into the solvent layer as it is formed.

The substantially water immiscible organic solvents that may be employed in carrying out the process of the present invention are benzene, ethyl acetate, chloroform, carbon tetrachloride, aniline, hexyl alcohol, xylene; and the like.

The water immiscible organic solvents as used in this invention extract the plutonium cupferride from aqueous solutions either by actual solution in the solvent or by preferential wetting by the solvent. In case of preferential wetting the plutonium cupferride may appear as a suspension or precipitate in the organic solvent owing to the fact that the plutonium cupferride is preferentially wetted by the solvent rather than by the water. It is to be understood throughout the present disclosure and appended claims that extraction by water immiscible organic solvents includes extraction by solvent action and/or preferential wetting action.

Formation of the plutonium cupferride may be effected by adding the cupferron or a solution thereof to the plutonium-containing solution and permitting the mixture to stand either with continuous or intermittent agitation for a suitable period of time, such as, for example, twenty-four to forty-eight hours. Heating under such circumstances is generally unnecessary.

The present invention may be further illustrated by the specific example which follows:

Example

To 5 ml. of a 20% solution of uranyl nitrate prepared from neutron irradiated uranium, said uranyl nitrate solution having a plutonium concentration of 372 alpha counts per minute, were added 3 drops of an aqueous 20% hydroxylamine hydrochloride solution. The resulting mixture was agitated for a period of one-half hour after which sufficient ammonium carbonate in the form of a saturated solution was added to bring the pH thereof up to a value of 8.0. Thereafter this solution was extracted three times with 1 ml. of chloroform containing two drops of 6% cupferron, each extraction being carried out with fresh solvent. The resulting extracts were combined and filtered after which the filtrate was placed in a platinum crucible and evaporated to dryness. The residue was ignited in order to free the extracted material from organic matter and thereafter was analyzed for its plutonium content by use of a suitable alpha pulse counter. This analysis indicated that the plutonium recovered amounted to a total of 371.6 alpha counts per minute.

It is to be understood that the above example and general description are merely illustrative of the present invention and should in no way be construed as limitative thereof. Other substitutes for ammonium carbo-

nate may be utilized to bring about the same results and the procedures herein set forth may be modified in numerous respects without departing from the broad embodiments of this invention. In general, it may be said that any modification or improvement that would normally occur to one skilled in the art is to be considered as lying within the scope of this invention.

What is claimed is:

1. In a process for the separation of plutonium from solutions containing that element together with uranium, fission products and other impurities commonly associated therewith, the steps which comprise contacting an acid solution containing plutonium in the tetravalent state and uranium in the hexavalent state with ammonium carbonate in an amount sufficient to render said solution alkaline, thereafter contacting said alkaline solution with cupferron and extracting the resulting mixture with a substantially water immiscible organic liquid solvent for the plutonium cupferride.
2. In a process for the separation of tetravalent plutonium from solutions containing that element together with hexavalent uranium and other impurities commonly associated therewith, the steps which comprise adding sufficient ammonium carbonate to said solutions to render said solution alkaline, and thereafter contacting the resultant solution with cupferron dissolved in a substantially water immiscible organic liquid solvent for the plutonium cupferride.
3. In a process for the separation of plutonium from solutions containing that element together with uranium, fission products and other impurities commonly associated therewith, the steps which comprise contacting an acid solution containing plutonium in the tetravalent state and uranium in the hexavalent state with a saturated aqueous solution of ammonium carbonate in an amount sufficient to render said solution slightly alkaline, thereafter contacting said alkaline solution with cupferron, and extracting the resulting mixture with a substantially water immiscible organic liquid solvent for the plutonium cupferride.
4. In a process for the separation of plutonium from solutions containing that element together with uranium, fission products, and other impurities commonly associated therewith the steps which comprise contacting an acid solution containing plutonium in the tetravalent state and uranium in the hexavalent state with a saturated aqueous solution of ammonium carbonate in an amount sufficient to render said solution slightly alkaline, thereafter contacting said alkaline solution with cupferron and extracting the resulting mixture with chloroform.
5. In a process for the separation of plutonium from solutions containing that element together with uranium and other impurities commonly associated therewith, the steps which comprise contacting an acid solution containing plutonium in the tetravalent state and uranium in the hexavalent state with a saturated aqueous solution of ammonium carbonate in an amount not substantially in excess of 10% over that required to neutralize said solution, thereafter contacting said solution with cupferron and extracting the resulting mixture with a substantially water immiscible organic liquid solvent for the plutonium cupferride.
6. The process of claim 5 in which the selective solvent is chloroform.
7. In a process for the separation of plutonium from solutions containing that element together with uranium, fission products, and other impurities commonly associated therewith, the steps which comprise contacting an acid solution containing plutonium in the tetravalent state and uranium in the hexavalent state with a sufficient quantity of ammonium carbonate to give a solution having a pH of about 8, thereafter contacting said solution with cupferron and extracting the resulting mixture with a substantially water immiscible organic liquid solvent for the plutonium cupferride thus formed.

8. In a process for the separation of plutonium from solutions containing that element together with uranium, fission products and other impurities commonly associated therewith, the steps which comprise contacting an acid solution containing plutonium in the tetravalent state and uranium in the hexavalent state with a sufficient quantity of ammonium carbonate to give a solution having a pH of about 8, thereafter contacting the resulting mixture with a solution comprising cupferron dissolved in a substantially water immiscible organic liquid solvent for the plutonium cupferride thus formed. 10

9. The process of claim 8 in which the selective solvent is chloroform.

10. In a process for the separation of plutonium from neutron irradiated uranyl nitrate hexahydrate solutions, the steps which comprise contacting said solution with ammonium carbonate in an amount sufficient to render said solution slightly alkaline and thereafter extracting said alkaline solution with a solution containing cupferron dissolved in a substantially water immiscible organic liquid solvent for the plutonium cupferride thus formed. 15

11. In a process for the separation of plutonium from neutron irradiated uranyl nitrate hexahydrate solutions, the steps which comprise adding sufficient ammonium carbonate thereto to give a solution having a pH of about 8 20

5

and thereafter contacting the resulting mixture with a chloroform solution of cupferron.

12. A process for the separation of plutonium from an aqueous alkaline ammonium carbonate solution containing plutonium values and uranium values, which comprises contacting said solution with cupferron so as to selectively form plutonium cupferride and separating said plutonium cupferride therefrom.
